UNITED STATES PATENT OFFICE

FREDERICK STONE, OF GLENDALE, CALIFORNIA, ASSIGNOR TO DOHENY-STONE DRILL CO., OF LOS ANGELES, CALIFORNIA, A CORPORATION OF DELAWARE

WELL DRILLING APPARATUS

Application filed January 4, 1928. Serial No. 244,422.

This application is a continuation, in part, of an application entitled "Earth boring machine" filed by me January 12, 1924, Serial No. 685,744 which has now matured as Patent 5 No. 1,678,307, July 24th, 1928.

The invention has to do generally with well drilling apparatus and is more particularly concerned with well drilling apparatus of the type shown in a patent issued to me 10 February 19, 1924, on "Rotary drill" No. 1,484,362. This type may be characterized as a rotary table having work-gripping means in its axial bore, the table being mounted for rotation within the axial bore of a cross head 15 which, in turn, is carried on hydraulically operated pistons for vertical reciprocation.

By virtue of this arrangement, it is possible to control the work with extreme ease and nicety of movement, the cross-head being 20 hydraulically operated in some situations to take a portion of the weight of the drill stem off the bit, in other situations to give added down-bearing force to the bit (in other words, to crowd the work down), and in still 25 other situations to elevate the work; the table being rotated at will throughout vertical movement of the cross-head. All these table and head movements are under the absolute control of the operator in spite of the fact 30 that the drilling apparatus, itself, and the work handled thereby are of very considerable weight and bulk, and the advantages of these features are well understood and appreciated by those skilled in the art.

35 There have heretofore been provided core drilling devices which embodied hydraulically operated cross-heads and means for rotating drill rods reciprocated by said heads. However, these devices are not at all suited 40 to the heavy duty work required of a machine used in drilling oil or artesian wells of usual size. And it is to be particularly noted that it requires more than a mere building up or strengthening of the individual elements of core drilling apparatus to adapt this 45 type of machine for well drilling purposes. This will be apparent when it is realized that the down-bearing load carried by the table often runs higher than 100,000 pounds, and to take this load and handle the work with

ease and dispatch under the varying situations in drilling operations, it is required not only that the apparatus be sizable and sturdy but that special precautions be taken to resist effectively the tremendous torsional and 55 down-bearing strains on the apparatus, so said strains may in no way impair the smoothness of operation and sensitivity of adjustment of the device. Furthermore, the nature of the operations which a well drilling 60 apparatus is called upon to perform, call for differences in structure over core drilling apparatus.

How the above is accomplished may be made apparent to better advantage in the 65 following detailed specification.

With the accomplishment of the above as one of the objects of the invention, it may be stated as another object to provide a device of the character described which is self-contained in nature, being adapted to take its driving power conveniently from any suitable power source. As one of the features, the means for guiding the cross-head during its vertical reciprocation are located entirely 70 below said cross-head, distinguishing advantageously from the prior art wherein dependence is had upon guide means horizontally offset from the cross-head for guiding it through its vertical path. This feature is 75 of advantage not only from the standpoint of providing guide means in a position best adapted to resist effectively the tremendous torsional strains set up in the apparatus and from the standpoint of rendering the appa- 80 ratus fully self-contained, but it also contributes to the end of providing apparatus which is fully accessible from all sides thereof, a characteristic of utmost importance, as is well understood by those familiar with the 85 conditions under which this type of apparatus is operated.

The fact that the table and cylinders are supported entirely from beneath and that there are no horizontally offset guide means 90 projecting into the path of workmen, render it possible to expose only the cross-head and table above the derrick floor, and the workmen have ready access to the table and appurtenances carried thereby, as a result being 95 100

able to handle the work with the speed, accuracy and safety so desirable in carrying out the operations incident to the use of this apparatus.

5 In addition to the particular manner in which I have fashioned the upper and lower members of the frame in which the cross-head is mounted for reciprocation (this particular manner having much to do with the 10 rigidity of the frame and its effectiveness in resisting the terrific stresses imposed thereon, as will be made apparent in the following description) these head members are so fashioned that they are adapted to support work 15 independently of the cross head. For instance, they may be adapted to support strings of casing or pipe, or, in certain situations, may be adapted to engage the same work as that taken by the head, though at 20 a different point. Thus, with the cross head gripping a stem above a joint and one of the frame heads gripping the stem below the joint, the two joint parts may be given relative rotation to make up or break the joint. 25 The gripping means in the two frame heads are centered with the gripping means in the cross head, it following that the different pieces of work engaged by the apparatus are positively centered, a feature of advantage 30 which will be obvious to those skilled in the art.

Other features of novelty and objects of the invention will be made apparent in the following detailed description, reference being had to the accompanying drawings in which:

Fig. 1 is a perspective view of a device embodying my invention;

Fig. 2 is a side elevation of the device, 40 shown partly in vertical, medial section;

Fig. 3 is a view generally similar to Fig. 2 but showing additional parts in elevation and additional work gripping members applied to the device;

Fig. 4 is a plan section on line 4—4 of Fig. 45 3; and

Fig. 5 is a plan section on line 5—5 of Fig. 3.

First, referring to Fig. 3, I have illustrated 50 a typical manner of installing the apparatus, though it will be distinctly understood that while this method of installation is preferable, it is in no way controlling on the invention, considered broadly. A pit or cellar

55 P is provided about the well bore B, supporting timbers T, resting on the ground surface G and spanning pit P. Supported on timbers T, in turn, are cross timbers T', and the derrick floor F is supported above timbers T'

60 and has a central opening O above the pit. The drilling apparatus may be considered as including a frame R disposed within pit P, a cross head C supported by frame R for vertical reciprocation through opening O, and a 65 rotary table S carried by the cross head. It

will be noted that frame R and all elements thereof are accessible from all sides within the pit, and that the only mechanism projecting above the derrick floor is the cross head, when it is elevated, and the rotary table, it following that free access to said table and its appurtenances is had by workmen on floor F.

Now referring particularly to Figs. 1 and 2, it will be seen that frame R includes vertically arranged cylinders 10, upper frame 75 head 11, and lower frame head 12, the lower head or base being mounted on skids 13 which rest on sills 13a extending across the pit at opposite sides of bore B.

Heads 11 and 12 are made up of heavy 80 castings secured to the opposite ends of the cylinders as at 14, the heads thus not only serving to tie the cylinders together but also being adapted to form the end closures therefor. The cylinders are preferably placed in 85 longitudinal compression through tie rods 15 which extend from skids 13 to the upper head 11, the frame structure thus being a particularly sturdy one and one which effectively resists the tendency of the various 90 operation and load strains to displace relatively the individual elements. It will be seen the frame heads serve to tie the cylinders together, and the cylinders, in turn, serve to 95 position the heads relatively.

The apparatus is placed within the pit so heads 11 and 12 extend horizontally over bore B, the cylinders being at opposite sides of said bore, and the upper and lower heads 11 and 12 are provided with axial bores 16 100 and 17, respectively, which are in vertical alinement with bore B.

Mounted within cylinders 10 are piston heads 18, the rods 19 thereof extending upwardly through the packed bearings 20 in 105 head 11, these bearings preferably being of appreciable vertical extent in order that they may serve effectively as guides co-acting with the piston rods in a manner tending to offset the torsional strains imposed on said head 110 when table S is rotated, though the rods and their guides are not depended upon for this function, as will be made apparent.

Connections 21 and 22 are provided at the upper and lower ends, respectively, of the 110 cylinder for the admission of fluid under pressure above or below the piston head in order that the rods 19 may be hydraulically raised, lowered, or controlled in their vertical reciprocation.

Cross head C extends from piston rod to piston rod over head 11, being gripped between the vertically spaced shoulders 23, 24, on each rod to hold the head against longitudinal movement with respect thereto, it following that reciprocation of rods 19 causes coincident and like reciprocation of the cross head.

Cross head C has an axial bore 25 which is in axial alinement with bores 16, 17 and B,

and taken for rotation within bore 25 is the rotary table S. The particular mounting of this table within the cross head is in no way controlling on the present invention, though the bearing arrangement illustrated is the subject-matter of the claim of Patent No. 1,678,307 on earth boring machines issued to me July 24, 1928. It will suffice to say that down and up-thrust bearings 26 and 27, respectively, are interposed between the table and the upper and lower sides of the cross head to hold said table against movement vertically with relation to the head, though allowing relative rotation therebetween; radial bearings 28 between the head and table being provided at the far sides of the end thrust bearing.

Table S has formed about its upper end or head portion 29 the gear teeth 30, with which teeth a pinion 31 meshes. Pinion 31 is secured to a vertically arranged driving spindle 32 which has usual rotational bearing in a sleeve 33 supported by box 34 extending horizontally from and secured to cross head C. Spindle 32 is of polygonal or key cross section, and extends downwardly through a polygonal bore in bevel pinion 35, the pinion hub 36 being mounted for rotation in the bearing box 37 which extends horizontally from head 11; boxes 33 and 37 being, of course, in axial alignment. Spindle 32, however, is adapted to slide vertically through pinion 35, though it has such fit therewith that rotation of the pinion imparts rotation to the spindle throughout vertical movement of the latter. It will be immediately recognized that the particular form of spindle and pinion engagement here shown is not at all controlling on the invention, for any of the suitable, well known systems for keying pinions and shafts together to prevent relative rotation but allow relative movement in the direction of their axes may be substituted for the particular means, here shown.

A power shaft 38 is journaled in the box 39 positioned on top head 11, the power shaft having a bevel pinion 40 in mesh with pinion 35. It will be evident that power may be applied to shaft 38 from any suitable source, and that rotation of said shaft acts through gears 40, 35, and shaft 32, and gears 31, 30, to rotate table S irrespective of the position to which said table is elevated or during vertical reciprocation of the table.

Means have been provided within the table for taking work which extends vertically through the bore 41 thereof, the gripping means preferably being of a nature which will impart rotative drive from the table or will connect the work to the table so the latter may be used for crowding the work down, controlling the work in its downward movement, or elevating the work. While I will describe very generally the particular grip-

ping and grip control means here disclosed, it will be understood this is in no way controlling on the present invention, though it is preferable for reasons given in my co-pending application entitled "Work gripping means for well drilling apparatus" filed January 4th, 1928 Ser. No. 244,423.

However, with this understanding that table S is adapted to support work, cause rotation thereof and control the work during its upward or downward movement or to force such upward or downward movement, and with the realization that this work often weighs over 100,000 pounds, it will be seen that the make-up of the device as described has much to do with insuring accurate, smooth working of the device in spite of the terrific strains imposed thereon.

In this connection it may now be stated that as a means for guiding the cross head in its vertical rotation and effectively aiding in resisting the torsional strains incident to table rotation, I preferably provide the vertically extending rods or posts 41a which are secured at their upper ends 42 to the cross head and extend downwardly with sliding fit through guide bosses 43 on top head 11. Preferably, these bosses extend vertically an appreciable distance in order that they may serve their purpose more effectively, particularly when the table is elevated. It will be seen that these guides take from the piston rods much of the duty of resisting torsional strains, and prevent binding action of the upper head on said piston rods which might otherwise result from said torsional strains.

It will be also noted that due to the inherent characteristics of the rigid, one-piece upper head through which all the pistons and guide rods extend and which, in turn, is rigidly tied to the rest of the frame, that the entire assembly is given great rigidity and power to resist the strains incident to the operation of the device.

It will also be noted that head 11 is supported not only from beneath by the cylinders, lower head and skids, but also that it preferably has horizontally extending portions 44 which overhang the cylinders and rest upon cross timbers T. The rigid nature and through extension of the upper head thus again comes into play inasmuch as it allows for this application of underlying supporting structure which is most effective in taking the down-bearing load both of the heavy structure of the drilling apparatus and of the terrific weight which is supported thereby at times.

The work gripping means shown within table bore 29 is generally indicated at 45 and includes segmental slips 46 movable vertically through the bore of table bushing 47 by such means as the lifting ring 48 under the actuation of lever 49. As noted above, this

showing and description of a particular gripping and grip actuating means is in no way controlling on the present invention. Slips 46 are of the usual character, that is, they have wedge characteristics whereby, when they are dropped in the bushing bore alongside work W, which here represents a drill stem, the wedge action of the slips tightly holds the work to the table against relative rotation, and, in certain situations, holds the work against vertical movement, with respect to the table, in either direction. A bridge clamp 46a may be bolted at 46b to the table across the slips and table bushing (to be described), to hold them down when the work is to be crowded down. It follows that rotation of the table imparts like movement to the work and that vertical reciprocation of the cross head through the piston mechanism described imparts like reciprocation to the work, this rotary movement or vertical reciprocation of the work being utilized for carrying out the well known operations expected of this type of apparatus.

So much of the apparatus as has thus far been described in detail is shown in my Patent No. 1,678,307, earth boring machines dated July 24th, 1928, and the above part of the instant specification may therefore be considered as a divisional continuation of the application which has matured, since the instant application was filed, into said patent.

It will be seen that due to the axial alignment of the various vertically extending bores of the apparatus, work W, in turn, is supported in axial alignment with bore B as well as with the frame head bores 16 and 17. Now under certain circumstances it is very desirable that several pieces of work be simultaneously supported by the drilling apparatus, and I utilize heads 11 and 12 for this purpose, they being particularly well adapted to take load supporting members due to their rigidity and to the fact that they are so tied together by the other elements of the apparatus that they are maintained in alignment both with each other and with the rotary table. It follows that work supported by either the upper or lower frame heads, or both, are held in true axial alignment with work held by table S and with bore B, the advantage of this feature being one which will be readily recognized by those skilled in the art and familiar with the very objectionable results emanating from conditions where the work is not positively held in alignment.

It will be distinctly understood that the particular character of the work supported by the rotary table or the frame heads depends entirely upon the operation in hand, suitable work gripping members being substituted in the various supporting members in accordance with well known practice. Therefore, while I have here shown work W in the form of a drill stem, it will be under-

stood the gripping means within table S may be readily changed to accommodate wash-over pipe or the like. In Fig. 2 I have illustrated stem W as being telescopically arranged within a casing 50 which extends through bore 17 to a point above head 12, and by way of illustrating the usefulness of the lower head for work supporting purposes, I have indicated casing 50 as being held to this head in axial coincidence with stem W by work gripping means generally indicated at 51.

While this gripping means may be of any desirable character, I have here shown it as including a head bushing 52 having a horizontal flange 53 resting on head 12 about bore 17, the sleeve portion 54 of the bushing extending through bore 17 and having a bore 55 which inclines inwardly and downwardly to take usual wedge slips 56. The head bushing is removably inserted within the head bore and it may have arcuate notches 56a (Fig. 5) engaging complementary faces 57 of cylinder collars 58 to prevent rotation of said bushing with respect to the head. I have here considered bushing 52 as a single member, but it will be understood it is preferably made up of two parts, as is usual, so it may be easily put to and pulled from place. Hold-down bolts 59, or any suitable substitute, may removably attach the bushing parts to the frame head for preventing said parts from being accidentally lifted up with the work. The above described showing of the work gripping means is to be considered purely as illustrative of and not restrictive on the invention. It will be seen that gripping means 51 is adapted to take the entire weight of pipe 50.

In Fig. 3 I have shown a slightly different situation wherein an outer casing 60 is supported by head 12 through slips 61 introduced in bushing 52. A smaller casing 62 extends telescopically through casing 60 and upwardly through the bore of upper head 11. Inserted within bore 16 is a head bushing 63 of a character generally similar to bushing 52 but having notches 64 taking the head ribs 65a to prevent rotation of the bushing parts with respect to the heads, usual segmental wedge slips 65 being introduced in the bushing bore to grip casing 62.

While any other suitable gripping means may be substituted, the illustrated form will serve to demonstrate how the upper head is adapted to support work and hold it definitely in axial alignment with stem W and casing 60. Bushing 63 and slips 65 may be readily inserted in the upper frame head when the cross head is elevated, and pin 66 may be passed through the flanges of the bushing and ribs 65a to hold the bushings from accidental upward displacement.

I have also shown means whereby slips 65 may be elevated to free them from casing 62.

While this means may be any suitable one, I have here shown a ring 67 surrounding pipe 62 below the bushing and having upwardly extending lugs 68 extending into the bushing bore beneath the slips. Ring 67 has lost motion connection 69 with lever 70, the latter being pivoted on a rod 71 extending between timbers T. An actuating lever 72 is pivoted on one of said timbers at 73 and has suitable connection at 74 with lever 70. It will be seen that proper movement of lever 72 swings lever 70 about fulcrum 71 to cause vertical, upward movement of ring 67 which, through lugs 68, moves slips 65 upwardly and out of operative engagement with pipe 62.

It will be understood that there are many different situations wherein it is desirable thus to provide for the support in predetermined relation of two or more pipe elements, but it is needless to mention them all for they will be readily apparent to those skilled in the art. However, it may be well to point out one or two of these situations as representative. In place of the slips 65 there may be substituted slips of the same work taking diameter as the slips 46. Drill stem W may then be adjusted through the table to bring a joint (not shown) thereof between slips 46 and the substituted slips in bushing 63. The slips in head 12 then serve to hold the drill pipe lengths below the joint against rotation, and by applying a suitable table-carried tool (not shown) to the drill pipe length above the table, said table may be rotated to rotate the upper lengths with respect to the lower, it thus being possible to utilize the apparatus as a joint make-up or break-down device, there being no necessity for elevators, spiders or other extraneous mechanism for supporting the drill pipe lengths below the table.

As another typical illustration, outer casings may be supported by either or both the slips in heads 11 and 12 and a string of wash-over pipe be supported by the table. The drill stem may then be extended through the wash-over pipe and supported from above by usual hoisting tackle. The wash-over pipe may then be vertically reciprocated by hydraulically operating the table, the constant movement of the wash-over pipe preventing it from becoming sanded-in, as will be readily understood.

It will be understood the drawings and description are to be considered merely as illustrative of and not restrictive on the broader claims appended hereto, for various changes in design, structure and arrangements may be made without departing from the spirit and scope of said claims.

I claim:

1. In a device of the character described, a plurality of horizontally spaced, vertically arranged cylinders, a stationary horizontal frame head extending between said cylinders,

said head being supported solely from beneath and having a vertically extending opening at a point between the cylinders, pistons within the cylinders and having piston rods extending upwardly above the head, a cross-head extending between and carried by the rods above the frame head and having a bore in alignment with the frame head opening, a table on the cross-head, above the cylinders, and mounted for rotation with respect thereto, said table having a bore in alignment with the cross-head opening, work grips on the table for gripping and taking the weight of work extending vertically through the table and cross-head bores and the frame head opening, and co-acting means on the cross head and frame head for guiding the cross-head during vertical movement imparted to it by the pistons, said co-acting means being located wholly below the cross-head throughout vertical reciprocation thereof.

2. In a device of the character described, a plurality of horizontally arranged, vertically spaced members having vertically aligned bores therethrough, independently operable mechanism on each of the members and having portions adapted to extend into the bores of their associated members, said mechanisms being adapted selectively to be operated to engage releasably work extending vertically through said bores, means for rotating one of the mechanisms and hence the work taken thereby, and means for vertically reciprocating said one mechanism and hence the work taken thereby.

3. In a device of the character described, a frame adapted to be positioned over a well bore, said frame embodying a plurality of vertically arranged cylinders spaced horizontally apart about the well bore, a frame head extending between and rigidly connecting the tops of the cylinders, said head having an opening adapted to be vertically aligned with the well bore, pistons within the cylinders and having piston rods extending upwardly through and guided by said head, a cross-head carried by and connecting the rods above the frame head and having a bore in axial alignment with said frame-head opening, said cross head being vertically movable by virtue of piston movement, a table having an axial bore and mounted for axial rotation on the cross-head above the frame head connecting the cylinders and held against movement vertically with respect to said cross-head, work gripping and supporting elements on the table for gripping and taking the weight of work adapted to extend vertically upward from the well bore through the frame-head opening and the bores of the cross-head and table, rotatable means carried by the frame-head and operatively connected to the table for rotating it, and co-acting guide means comprising rods on the

cross head and guides on the frame head surrounding said rods for guiding said cross head in its vertical movement and relieving said piston rods of torsional strains set up by 5 virtue of table rotation.

4. In a device of the character described, a frame adapted to be positioned over a well bore, said frame embodying a plurality of vertically arranged cylinders spaced hori-

10 zontally apart about the well bore, a frame head extending between and rigidly connecting the tops of the cylinders, said head having an opening adapted to be vertically alined with the well bore, pistons within the cylin-

15 ders and having piston rods extending upwardly through and guided by said head, a cross-head carried by and connecting the rods above the frame head and having a bore in axial alinement with said frame-head open-

20 ing, said cross head being vertically movable by virtue of piston movement, a table having an axial bore and mounted for axial rotation on the cross-head and held against movement vertically with respect thereto, work

25 gripping and supporting elements on the table, entirely above the frame head connecting the cylinders, for gripping and taking the weight of work adapted to extend vertically upward from the well bore through the

30 frame-head opening and the bores of the cross head and table, rotatable means carried by the frame-head and operatively connected to the table for rotating it, vertically extending and elongated bosses on the frame head, at

35 the tops of the cylinders, and guide rods extending downwardly from the cross head through said bosses to guide the cross head in its vertical reciprocation and to relieve said piston rods of torsional strains set up by table

40 rotation.

5. In a device of the character described, a frame adapted to be positioned over a well bore, said frame embodying a plurality of vertically arranged cylinders spaced hori-

45 zontally apart about the well bore, a frame head extending between and rigidly connecting the tops of the cylinders, said head having an opening adapted to be vertically alined with the well bore, pistons within the cylin-

50 ders and having piston rods extending upwardly through and guided by said head, a cross-head carried by and connecting the rods above the frame head and having a bore in axial alinement with said frame-head open-

55 ing, said cross head being vertically movable by virtue of piston movement, a table having an axial bore and mounted for axial rotation on the cross-head, above the frame head at the tops of the cylinders, and held against

60 movement vertically with respect to said cross-head, work gripping and supporting elements on the table for gripping and taking the weight of work adapted to extend vertically upward from the well bore through

65 the frame-head opening and the bores of the

cross-head and table, a vertically arranged drive spindle horizontally offset from the table axis, a pair of bearings for the spindle arranged one on the cross head and one on the frame head, the spindle and one of the 70 bearings being arranged for relative vertical movement, an operative connection between the spindle and table whereby spindle rotation rotates the table, and means for rotating the spindle.

6. In a device of the character described, a frame adapted to be positioned over a well bore, said frame embodying a plurality of vertically arranged cylinders spaced hori-

80 zontally apart about the well bore, a frame head extending between and rigidly connecting the tops of the cylinders, said head having an opening adapted to be vertically alined with the well bore, pistons within the cylinders and having piston rods extending

85 upwardly through and guided by said head, a cross-head carried by and connecting the rods above the frame head and having a bore in axial alinement with said frame-head

opening, said cross head being vertically movable by virtue of piston movement, a table having an axial bore and mounted for axial rotation on the cross-head and held against movement vertically with respect

90 thereto, work gripping and supporting elements on the table for gripping and taking the weight of work adapted to extend vertically upward from the well bore through the frame-head opening and the bores of the

95 cross-head and table, a vertically arranged drive spindle horizontally offset from the table axis, a pair of bearings for the spindle arranged one on the cross head and one on the frame head, the spindle and one of the

100 bearings being arranged for relative vertical movement, an operative connection between the spindle and table whereby spindle rotation rotates the table, a bevel gear mounted on the frame head for rotation, a sliding

105 spline connection between the spindle and gear whereby they are capable of relative vertical movement and held against relative rotation, a horizontal power shaft journaled on the frame head, and a bevel gear keyed to said power shaft and meshed with the

110 first mentioned bevel gear.

7. In a device of the character described, a frame adapted to be positioned over a well bore, said frame embodying a plurality of vertically arranged cylinders spaced hori-

115 zontally apart about the well bore, a frame head extending between and rigidly connecting the tops of the cylinders, said head having an opening adapted to be vertically alined with the well bore, pistons within the cylinders

120 and having piston rods extending upwardly through and guided by said head, a cross-head carried by and connecting the rods above the frame head and having a bore in axial alinement with said frame-head open-

- ing, said cross head being vertically movable by virtue of piston movement, a table having an axial bore and mounted for axial rotation on the cross-head above the frame-head
 5 at the tops of the cylinders and held against movement vertically with respect to said cross-head, work gripping and supporting elements on the table for gripping and taking the weight of work adapted to extend vertically upward from the well bore through the frame-head opening and the bores of the cross-head and table, rotatable means carried by the frame-head and operatively connected to the table for rotating it, and coacting guide means on the frame head and the underside of the cross-head for guiding said cross-head solely from beneath in its vertical movement and relieving said piston rods of torsional strains set up by virtue of table rotation.
8. In a device of the character described, a frame adapted to be positioned over a well bore, said frame embodying a plurality of vertically arranged cylinders spaced horizontally apart about the well bore, a frame head extending between and rigidly connecting the tops of the cylinders, said head having an opening adapted to be vertically aligned with the well bore, pistons within the cylinders and having piston rods extending upwardly through and guided by said head, a cross head carried by and connecting the rods above the frame head and having a bore in axial alignment with said frame-head opening, said cross head being vertically movable by virtue of piston movement, a table having an axial bore and mounted for axial rotation on the cross-head above the horizontal plane of the tops of the cylinders and held against movement vertically with respect to said cross-head, work gripping and supporting elements on the table for gripping and taking the weight of work adapted to extend vertically upward from the well bore through the frame-head opening and the bores of the cross-head and table, rotatable means carried by the frame-head and operatively connected to the table for rotating it, and work-gripping and supporting elements on said frame head at the tops of the cylinders and in alignment with the gripping elements on said table for supporting work below the cross-head.
9. In a device of the character described, a frame adapted to be positioned over a well bore, said frame embodying a plurality of vertically arranged cylinders spaced horizontally apart about the well bore, an upper frame head extending between and rigidly connecting the tops of the cylinders, said head having an opening adapted to be vertically aligned with the well bore, a lower frame head extending between and rigidly connecting the lower ends of the cylinders and having an opening aligned with the opening in the upper frame head, pistons within the cylinders and having piston rods extending upwardly through and guided by said upper head, a cross-head carried by and connecting the rods above the upper frame head and having a bore in axial alignment with said frame-head openings, said cross head being vertically movable by virtue of piston movement, a table having an axial bore and mounted for axial rotation on the cross-head, above the horizontal plane of the tops of the cylinders, and held against movement vertically with respect to said cross-head, work gripping and supporting elements on the table for gripping and taking the weight of work adapted to extend vertically upward from the well bore through the frame-head openings and the bores of the cross-head and table, rotatable means carried by the upper frame-head and operatively connected to the table for rotating it, and work-gripping and supporting elements on each of said frame heads and in alignment with the gripping elements on said table for supporting work below the cross-head.
10. In a device of the character described, a frame adapted to be positioned over a well bore, said frame embodying a plurality of vertically arranged cylinders spaced horizontally apart about the well bore, an upper frame head extending between and rigidly connecting the tops of the cylinders, said head having an opening adapted to be vertically aligned with the well bore, a lower frame head extending between and rigidly connecting the lower ends of the cylinders and having an opening aligned with the opening in the upper frame head, pistons within the cylinders and having piston rods extending upwardly through and guided by said upper head, a cross-head carried by and connecting the rods above the upper frame head and having a bore in axial alignment with said frame-head openings, said cross head being vertically movable by virtue of piston movement, a table having an axial bore and mounted for axial rotation on the cross-head and held against movement vertically with respect thereto, work gripping and supporting elements on the table for gripping and taking the weight of work adapted to extend vertically upward from the well bore through the frame-head openings and the bores of the cross-head and table, rotatable means carried by the upper frame-head and operatively connected to the table for rotating it, and work-gripping and supporting elements on one of said frame heads and in alignment with the gripping elements on said table for supporting work below the cross-head.
11. In a device of the character described, a frame adapted to be positioned over a well bore, said frame embodying a plurality of vertically arranged cylinders spaced horizontally apart about the well bore, a frame

head extending between and rigidly connecting the tops of the cylinders, said head having an opening adapted to be vertically aligned with the well bore, pistons within the cylinders and having piston rods extending upwardly through and guided by said head, a cross-head carried by and connecting the rods above the frame head and having a bore in axial alignment with said frame-head opening, said cross head being vertically movable by virtue of piston movement, a table having an axial bore and mounted for axial rotation on the cross-head and held against movement vertically with respect thereto, work gripping and supporting elements on the table for gripping and taking the weight of work adapted to extend vertically upward from the well bore through the frame-head opening and the bores of the cross-head and table, rotatable means carried by the frame-head and operatively connected to the table for rotating it, extensions on said frame head extending horizontally outwardly beyond the cylinders, and supporting members extending beneath said extensions.

25 In witness that I claim the foregoing I have hereunto subscribed my name this 31st day of December, 1927.

FREDERICK STONE.
